UNITED STATES PATENT OFFICE.

FREDERICK PARKER VIZE AND HENRY JOHN BRODERICK, OF ECHUCA, VICTORIA,
AUSTRALIA.

BRUSH.

No. 890,204.

Specification of Letters Patent.

Patented June 9, 1908.

Application filed April 25, 1907. Serial No. 370,131.

To all whom it may concern:

Be it known that we, FREDERICK PARKER VIZE and HENRY JOHN BRODERICK, subjects of the King of Great Britain, residing at 5 Echuca, in the State of Victoria, in the Commonwealth of Australia, have invented certain new and useful Improvements in Brushes; and we do hereby declare the following to be a full, clear, and exact description 10 of the invention, such as will enable others skilled in the art to which it appertains to make and use the same.

The object of this invention primarily is to provide in a light, compact and inexpensive 15 form an improved reservoir brush of that description in which the color or other fluid (hereinafter referred to as color for the purpose of brevity) may be drawn from the bowl or other receptacle into a fountain or 20 reservoir formed in the brush handle and forced at will therefrom through a suitable outlet to the hairs or fibers of the brush.

Another object of the invention is to provide means whereby the color contained in 25 the reservoir or fountain may be conveniently discharged through an opening formed within the brush holder in a uniform flow. This opening is regulated by a valve which is 30 conveniently adjusted by the relative positioning of the brush-holder and the brush handle.

Referring now to the accompanying sheet of drawings which illustrate the invention.

Figure 1 is a longitudinal vertical section 35 of the brush showing the color inlet to the handle reservoir in its closed position. Fig. 2 is a half side view and half sectional view of the brush with the color inlet open and the rear portion of the handle drawn outwardly, 40 in which positions the reservoir is ready to be charged with color and also illustrates a modification of the construction of some of the parts.

In these views the numeral 1 designates 45 the brush material which may be composed of hair, bristles or fibers.

2 is the brush holder which is preferably of the design illustrated and constructed with a shank 3 designed to fit into a tubular case 4 50 which forms the color receiving chamber or reservoir. The brush holder 2 may either be fitted tightly and telescopically into the casing 4 as is illustrated in Fig. 1 or it may be screwed thereinto as shown in Fig. 2.

55 5 is a truncated conical shaped chamber

open at both ends through which the color is drawn when the reservoir 4 is being charged, and through which the color is discharged to the hairs or fibers 1 of the brush.

6 is a valve secured to the end of a longitudinal rod 7 placed in the interior of the reservoir and secured in position by means of a fixed ring 8.

The back portion of the brush handle is indicated by 9, and it is illustrated in the form 65 of an outer casing or ferrule designed to fit air-tight over the reservoir casing 4 and to be capable of telescopic movement thereon.

In operation the brush-holder 2 is drawn or screwed outwardly from the casing 4 at 70 any required distance as illustrated in Fig. 2 thereby forming an inlet to the valve chamber 5, and the hairs, bristles or fibers 1 of the brush are rested firmly in the bowl or other receptacle containing the color. The outer 75 casing 9 is then drawn outwardly and operates similar to a suction plunger and the chamber or reservoir is simultaneously charged with color. The brush-holder 2 is then twisted or screwed back into the ferrule 80 or color casing 4 to a sufficient extent to regulate the opening to and from the valve chamber 5 by means of the relative position of the valve 6. By these means when the outer casing 9 is moved forwardly towards 85 the brush proper by the user the color flows uniformly and in a regulated quantity to the hairs or fibers of the brush.

The parts of the brush may be made of any suitable material, but the portions which 90 come in contact with the color are preferably made of brass in order to prevent corrosion. It will be well understood, however, that sundry modifications in the design and details of the invention may be made while 95 still retaining essential features.

What we claim as our invention, and desire to secure by Letters Patent, is:—

1. In a brush, a color reservoir formed in the handle, a movable brush-holder, which has a tube arranged therein constituting the outlet from the reservoir, inserted in said handle, a valve adapted to control the inlet to and outlet from the color reservoir by the relative positioning of the brush holder 100 within the color reservoir, and a sleeve closed at one end fitting over said color reservoir capable of telescopic movement thereon and constituting a plunger for said reservoir.

2. In a brush, a color reservoir formed in 110

the handle, a movable brush holder having arranged therein a truncated conical chamber open at both ends, said holder being inserted in the reservoir and adapted to control the inlet to and outlet from the reservoir by the relative positioning thereof within the said reservoir, a valve affixed at the end of a longitudinal rod secured within the reservoir, and a sleeve fitting over said color reservoir capable of telescopic movement thereon, for the purposes herein described.

3. In a brush, the combination with a handle constituting a color reservoir, a brush holder longitudinally movable in one end of said handle and having an opening in communication with said reservoir, the other end of said handle being open and carrying a telescopic sleeve closed at its end and constituting a plunger for drawing color into and expressing the same from said reservoir, and

a valve for controlling said brush holder opening and adapted to be actuated by the relative position of the brush holder within the color reservoir.

4. In a brush, a brush-holder 2 having a shank 3 having screw threaded connection with the handle 4, a chamber 5 arranged within the brush-holder, a valve 6 affixed at the end of a longitudinal rod 7 secured with the handle 4 by means of a ring 8, and a sleeve 9 fitting over the handle 4 and capable of telescopic movement thereon.

In testimony whereof we have signed this specification in the presence of two witnesses.

FREDERICK PARKER VIZE.
HENRY JOHN BRODERICK.
